CLAIM

The ornamental design for a jock cup, as shown and described.

DESCRIPTION

FIG. 1 is a perspective view of a jock cup embodying my design;

FIG. 2 is a front view of a jock cup embodying my design;

FIG. 3 is a rear view of a jock cup embodying my; and,

FIG. 4 is a side view of a jock cup embodying my design.

Although FIG. 4 shows a view of one side of the jock cup, it should be appreciated that the other side of the jock cup is a mirror image of the illustrated side.
